CLAIM

The ornamental design for a slant top gaming machine, as shown and described.

DESCRIPTION

FIG. 1 is an isometric view of a slant top gaming machine in accordance with the present invention;

FIG. 2 is a top view of the slant top gaming machine of FIG. 1;

FIG. 3 is a front view of the slant top gaming machine of FIG. 1;

FIG. 4 is a side view of the slant top gaming machine of FIG. 1;

FIG. 5 is a back view of the slant top gaming machine of FIG. 1; and,

FIG. 6 is a bottom view of the slant top gaming machine of FIG. 1.

The portion of the figures shown in dotted lines represent gaming machine components and forms no portion of the claimed design.
